UNITED STATES PATENT OFFICE

105,215

DESIGN FOR A COMBINED BACK GUARD AND LAMP SHADE FOR RANGES

Donald L. Hadley, Mansfield, Ohio, assignor to
The Tappan Stove Company, Mansfield, Ohio, a corporation of Ohio

Application March 22, 1937, Serial No. 68,336

Term of patent 3½ years

To all whom it may concern:

Be it known that I, Donald L. Hadley, a citizen of the United States, residing at Mansfield, in the county of Richland and State of Ohio, have invented a new, original, and ornamental Design for Combined Back Guard and Lamp Shade for Ranges, of which the following is a specification, reference being had to the accompanying drawing, forming part thereof, wherein Fig. 1 is a view in front elevation of a combined back guard and lamp shade for ranges; Fig. 2 is a top plan view of the same and Fig. 3 is a view in end elevation, of a combined back guard and lamp shade for ranges, showing my new design.

The dominant feature of the design resides in the combined back guard and lamp shade for ranges, shown in full lines.

I claim:

The ornamental design for a combined back guard and lamp shade for ranges, substantially as shown and described.
